[57] CLAIM

The ornamental design for a covered well for bathtubs, as shown and described.

DESCRIPTION

FIG. 1 is a perspective view of a covered well for bathtubs showing my new design;

FIG. 2 is an enlarged perspective view taken on line 2—2 of FIG. 1 with the cover in an open position; and FIG. 3 is a perspective view taken on line 3—3 of FIG. 2 with the cover removed.

The broken line showing of a bathtub in FIG. 1 is for purposes of illustration only and forms no part of the claimed design.
